by *Samuel L. [Signature]*
Attorney

JOHN NORRIS, OF MOUNT PLEASANT, MARYLAND.

Letters Patent No. 83,199, dated October 20, 1868.

HOT-AIR ATTACHMENT TO COOKING-STOVES.

The Schedule referred to in these Letters Patent and making part of the same.

To all whom it may concern:

Be it known that I, JOHN NORRIS, of Mount Pleasant, in the county of Frederick, and State of Maryland, have invented a new and improved Heating-Attachment for Stoves; and I do hereby declare that the following is a full, clear, and exact description of the construction and operation of the same, reference being had to the accompanying drawings, making a part of this specification, in which—

Figure 1 is an outline sectional view, showing the construction of the stove to which my invention is commonly applied.

Figure 2 is a side view of the stove, with my improvement attached.

Figure 3 is a detached view, showing the collar and cap.

Figure 4 is a view of my improvement, as applied to a common cooking-stove.

This invention is an improvement upon the "ten-plate" stove, and consists in constructing one of the oven-doors of the same with a bay, from the top of which projects a short tube or collar, which conveys heated air to the upper apartments of the house, by means of suitable pipes, and also, when the pipes are removed, serves for certain culinary purposes, as hereinafter more fully described.

In the drawings, fig. 1 represents a longitudinal vertical section, through the centre of a "ten-plate" stove, A being the fire-chamber of said stove; B, the oven; B', one of the oven-doors, on the side of the stove; C, the fire-chamber door and air-draught; and D, the smoke-flue; the current of air passing from the door C to the flue D, around the rear end of the oven, as shown by the red arrows.

The door B' is constructed with a deep bay, E, from the top of which projects a short tube or collar, E'. A pipe, F, rests upon this tube, and extends to the apartment on the next floor above, being jointed, as at f, in one or more places, so as to have a slight flexibility. This pipe is provided with a cap, m, to cover its upper end, and another, e, is provided, to cover the tube or collar E', when the pipe is disconnected from the latter.

When the oven-door is closed, and the pipe F attached, as seen in fig. 2, the hot air will pass from the oven to the chamber above. If the occupants of the

chamber desire to shut off the draught into their apartment, all they have to do is to place the cap m on the top of the pipe; and if the occupants of the room in which the stove is situated desire to stop the escape of hot air from the stove to the chamber above, they can at once accomplish it by lifting the pipe off of the collar or tube, the lower portion of the pipe sliding easily in the upper portion by means of the telescopic joint f. When it is desired to use the oven for the purpose of baking any article of food, the pipe should be disconnected from the collar E', and the latter closed by the cover or cap, e.

Instead of attaching the bay to the oven-door of a "ten-plate" stove, it might be made with a flange, r, as seen in fig. 4, and be used in connection with the common cooking-stoves, being bolted through the flange to their rear side, under the stove-pipe. A register, s, for the purpose of supplying air, might be provided in the bottom of the bay, when used in this manner. The apparatus could thus be applied to any old stove in a farmer's kitchen, without the trouble of taking it to a blacksmith to be fitted and attached.

My object, in fact, in the whole invention, is not so much to improve the method of originally casting the stove itself, as to furnish a convenient attachment, in the shape of an attachable and detachable sheet-iron oven-door, provided with a bay, as above described, which can be employed in connection with the old "ten-plate" stoves, for many years in use among the people of my vicinity, and which can be as readily affixed to an old stove in the kitchen, as to a new one at the foundry.

Having thus described my invention,

What I claim as new, and desire to secure by Letters Patent, is—

As an attachment to a "ten-plate" stove, the oven-door, constructed with a bay, E, and collar E', and having connected therewith the pipe F, provided with the caps e m, the whole operating in the manner and for the purposes specified.

JOHN NORRIS.
